US00D607421S

(12) **United States Design Patent**
Park et al.

(10) **Patent No.:** US D607,421 S
(45) **Date of Patent:** ** Jan. 5, 2010

(54) **LIGHT EMITTING DIODE**

(75) Inventors: **Gwui-Youn Park**, Seoul (KR); **Chi-Ok In**, Chungcheongnam-do (KR); **Hyun-Ho Shin**, Yongin-si (KR)

(73) Assignee: **Alti-Electronics Co., Ltd** (KR)

(**) Term: **14 Years**

(21) Appl. No.: **29/328,520**

(22) Filed: **Nov. 25, 2008**

(30) **Foreign Application Priority Data**

May 27, 2008 (KR) 30-2008-0022385

(51) **LOC (9) Cl.** 13-03

(52) **U.S. Cl.** D13/180

(58) **Field of Classification Search** D13/180; D26/2; 257/79, 80, 81, 88, 89, 95, 98, 99, 257/100; 313/483, 498, 500; 362/555, 800

(57) **CLAIM**

The ornamental design for a light emitting diode, as shown and described.

DESCRIPTION

FIG. 1 is a perspective view of a light emitting diode showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom perspective view thereof.
